UNITED STATES PATENT OFFICE.

OLIVER P. MEGAHAN, OF WESTERVILLE, OHIO.

INSULATOR-SUPPORT.

1,029,207.

Specification of Letters Patent. Patented June 11, 1912.

Application filed July 18, 1911. Serial No. 639,128.

To all whom it may concern:

Be it known that I, OLIVER P. MEGAHAN, a citizen of the United States, residing at Westerville, in the county of Franklin and State of Ohio, have invented certain new and useful Improvements in Insulator-Supports, of which the following is a specification.

The present invention relates to improvements in insulator supports.

The object of the invention is the provision of a cross arm having wire supporting devices of novel form which are efficient and durable and will prevent falling of the wire should a break occur; to provide a rigid and compact joint between the cross arm and pole; and generally to improve the construction of devices of this character as will be hereinafter set forth.

20 The invention consists in certain novel features of construction and combinations and arrangements of parts as illustrated in the drawings and more particularly pointed out in the claim.

25 The accompanying drawings illustrate one complete example of the embodiment of the invention, and a modification thereof, constructed according to the best mode I have so far devised for the practical application of the principles.

Figure 1 is an elevation of the top of a pole with the cross arm attached thereto. Fig. 2 is a side elevation of Fig. 1. Fig. 3 is a view of a single hanging pin. Fig. 4 is a view of a double hanging pin. Fig. 5 is a view of a single top pin. Fig. 6 is a partial side elevation of the cross arm showing form of hanging pin with modified attaching means. Fig. 7 is a side view of Fig. 6. Fig. 8 is an enlarged sectional view of the cross arm showing reinforcing construction and perforation for insulator pins. Fig. 9 is a sectional view of the cross arm with metallic thimble or socket for the insulator pin. Fig. 10 is a side elevation of pole showing stay rods and manner of securing the arm to the pole and space left for adjustment.

50 The pole 1 may be of wood or concrete construction and is provided with a recess or socket 2 for the reception of an edge portion of the cross arm 3. The cross arm is

composed of concrete reinforced with longitudinal bars 4 and connecting wires or bars 5, and is preferably A-shape in cross section 55 for securing strength combined with lightness in weight. The cross arm is secured to the pole by means of a strap bent, as in Figs. 2 and 10, to conform to the shape of the cross arm and secured by bolts 7 and 8 60 to the pole. A pair of metallic stays or brace bars 9 are bolted at 10 to the pole and the free end of each bar is twisted and perforated as at 11 for attachment to the under side of the cross arm. 65

In Fig. 1 two forms of insulator pins are illustrated, as means for securing the brace bars to the cross arm. The single hanging pin 12 is provided with a U-shaped bend 13 upon which the insulator 14 is supported. 70 The threaded end 15 of the rod with the lower nut 16 thereon is passed through the perforated end 11 of the stay arm 9 and the opening 17 in the cross arm, and the bar is clamped in position by the upper nut 18. 75 The double hanging pin 19 is identical with the single pin 12, but has a longer threaded end upon which may be placed an upper insulator 14'. In some instances the hanger pin may be formed with a hook 20, as shown 80 in Figs. 6 and 7. In this case the hook is perforated and the usual bolt 21 is passed therethrough, through the cross arm and also through the perforated end 11 of the stay bar 9. It will be understood that the 85 bolt 21, (Fig. 5) may also be used to support an insulator, as at the right end of Fig. 1. A further modification is illustrated in Fig. 9 wherein the cross arm has embedded therein a metallic socket 22 for 90 the reception of the insulator pin which may be of wood or metal, and to drain off moisture, the lower end of the metallic thimble or socket is perforated at 23 which aligns with the perforation 24 of the cross 95 arm. Under certain conditions, wood strips, indicated at 25 (Fig. 8) may be laid on top of the cross arm and under the pins, as a non-conductor or wear plate for the wire which might become loose and drop 100 onto the arm. And wood lined hangers 26 (Fig. 6) may also be used for the same purpose on the lower insulator pins.

Having thus fully described my inven-

tion, what I claim as new and desire to secure by Letters Patent is:—

The combination with a cross arm of a support formed with an upwardly bent lower hooked end having an insulator thereon, a flat perforated upper end shaped with a downwardly bent hook engaging the arm and suspended thereover, and a fastening

bolt passed through said hook and arm and having a second insulator thereon.

10

In testimony whereof I affix my signature in presence of two witnesses.

OLIVER P. MEGAHAN.
